[57] **CLAIM**

The ornamental design for a bracket for conduits, substantially as shown and described.

DESCRIPTION

FIG. 1 is a perspective view of one side of the bracket for conduits showing my new design;

FIG. 2 is a perspective view showing the opposite side thereof, with the broken lines showing the environmental use of my design;

FIG. 3 is a side elevation view thereof; and

FIG. 4 is an end elevation view thereof.
